UNITED STATES PATENT OFFICE.

DARWIN V. MILLER, OF WEEDSPORT, NEW YORK, ASSIGNOR TO THE WEEDSPORT SKIRT AND DRESS COMPANY, OF SAME PLACE.

BUSTLE.

SPECIFICATION forming part of Letters Patent No. 391,757, dated October 23, 1888.

Application filed February 23, 1888. Serial No. 264,952. (No model.)

To all whom it may concern:

Be it known that I, DARWIN V. MILLER, a citizen of the United States, residing at Weedsport, in the county of Cayuga and State of New York, have invented new and useful Improvements in Bustles, of which the following is a specification.

This invention consists in a bustle constructed as hereinafter described and claimed, reference being had to the accompanying drawings, in which—

Figure 1 is a perspective view of my improved bustle, and Figs. 2 and 3 are detail views of the same.

15 The bustle-frame comprises an upper bow, 1, a lower bow, 2, and several intermediate bows, 3, 4, and 5, of any suitable number. This frame is provided with a covering, 6, of any appropriate character, and to which is attached 20 a waistband, 7, of ordinary construction.

The upper bow, 1, consists of a flat, elastic, metallic or whalebone strip closely covered with textile material, and having riveted to each end, on its outer side, a short textile-covered supplemental strip, 8, of metal or whalebone, arranged in such a manner as to form a bifurcation, 9, at each end of the bow. Any required number of rivets, 10, or other suitable connections may be used to secure a 25 firm union between the strips 8 and the main portion 1 of the upper bow. In the forward ends of the bifurcations formed by the bow 1 and supplemental strips 8 are secured studs or elongated rivets 11, which serve as bearings for 30 the lower and intermediate bows, which are 35 preferably made of metallic wire. The opposite ends of the lower bow, 2, are passed around the studs 11 adjacent to the upper bow, 1, and are bent to form spring-arms 2^a, having at their 40 ends eyes 2^b, that engage the adjacent intermediate bow, 3, as shown. This intermediate bow, 3, also engages the studs 11, and has 45 spring-arms 3^a, provided with eyes 3^b, to engage the next intermediate bow, 4, which in turn has spring-arms 4^a and eyes 4^b, whereby

it engages the studs 11 and the next intermediate bow, 5, in the same manner. The uppermost intermediate bow, 5, is made to engage the studs 11 next to the supplemental strips 8, and is provided with arms 5^a, having 50 eyes 5^b, that engage the forward rivets 10 between the upper bow, 1, and attached supplemental strips. It will thus be seen that the attaching-arms of the lower and intermediate bows serve as springs to spread the bows apart 55 and give the proper shape to the bustle. A connecting strap or cord, 12, may be attached centrally to each bow for the purpose of limiting the spread of the bustle, and a back-strap, 13, is provided, as usual, to regulate the set. 60

What I claim as my invention is—

1. A bustle comprising in its structure a vertical elastic bow having bifurcated lower ends, a transverse stud or bearing at or near the extremity of each bifurcated end, and other bows having their end portions mounted on the said studs or bearings between the bifurcations, substantially as described. 65

2. A bustle-frame comprising an upper bow having bifurcated ends with studs or bearings secured therein, and a lower bow, and intermediate bows engaged with said studs and provided with arms having eyes engaged with the adjacent bows, substantially as described. 70

3. A bustle-frame comprising an upper bow, 75 1, having supplemental strips 8 secured to the ends, studs 11, secured in the bifurcations between the forward ends of said bow and strips, and a lower bow, 2, and intermediate bows, 3, 4, and 5, engaged with said studs, said lower bow 80 and intermediate bows being each provided with arms that are engaged with the next bow above in succession, substantially as described.

In testimony whereof I affix my signature in presence of two witnesses.

DARWIN V. MILLER.
